HANDLE FOR A COMPRESSED GAS SOLDERING TORCH OR THE LIKE

Robert J. Smith, 1267 Plymouth Ave. NE.,
Massillon, Ohio

Filed Oct. 28, 1963, Ser. No. 77,164

Term of patent 14 years

(Cl. D44—29)

FIG. 1 is an elevational view of a handle for a compressed gas soldering torch or the like showing my new design;

FIG. 2 is a top plan view thereof on an enlarged scale;

FIG. 3 is a side elevational view thereof;

FIG. 4 is an end elevational view taken from the right of FIG. 3; and

FIG. 5 is a sectional view taken on line 5—5 of FIG. 3.

The broken lines shown in FIG. 1 are for illustrative purposes only.

I claim:

The ornamental design for a handle for a compressed gas soldering torch as the like, substantially as shown and described.
